UNITED STATES PATENT OFFICE.

JOSEPH NORMAN KLEMA, OF AUSTIN, MINNESOTA.

LANTERN.

1,313,390.

Specification of Letters Patent.

Patented Aug. 19, 1919.

Application filed November 20, 1918. Serial No. 263,336.

To all whom it may concern:

Be it known that I, JOSEPH N. KLEMA, a citizen of the United States, residing at Austin, in the county of Mower and State 5 of Minnesota, have invented certain new and useful Improvements in Lanterns, of which the following is a specification, reference being had to the accompanying drawings.

10 This invention relates to certain improvements in lanterns, and has relation more particularly to a device of this general character of a hand type, and it is an object of the invention to provide a device of this general character having novel and improved means whereby a color screen may be adjusted relative to the burner as the occasions of practice may require.

It is also an object of the invention to 20 provide a lantern of this type embodying a casing in which is supported the burner and into which extends a screen holder provided with means whereby the holder may be raised or lowered as required to properly 25 position the color screen carried by the holder, together with novel and improved means carried by the casing and coacting with the holder for maintaining the holder in raised position.

30 The invention consists in the details of construction and in the combination and arrangement of the several parts of my improved lantern whereby certain important advantages are attained and the device rendered simpler, less expensive and otherwise 35 more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in elevation of a lantern constructed in accordance with an embodiment of my invention;

Fig. 2 is a view in bottom plan of my improved lantern as disclosed in Fig. 1;

Fig. 3 is an enlarged fragmentary view 50 partly in vertical section and partly in elevation of my improved lantern as herein set forth.

Fig. 4 is a view in perspective of a holder and coacting color screen as herein included;

Fig. 5 is an enlarged sectional view taken 55 substantially on the line 5—5 of Fig. 1;

Fig. 6 is a fragmentary view in perspective illustrating a handle constructed in accordance with a further embodiment of my invention; and

Fig. 7 is a fragmentary view partly in section and partly in elevation illustrating a handle constructed in accordance with a still further embodiment of my invention.

As disclosed in the accompanying drawings, F denotes a frame of conventional type and which includes a base ring 1, a top ring 2 and radially arranged side members 3. Coacting with the top ring 2 is the top T of a conventional construction.

The lower portions of the members 3 are provided adjacent their lower ends with the inwardly directed knees 5 soldered or otherwise affixed to the upper end portion of a casing C arranged within the frame. The 75 top or upper face of the casing C is open and the lower or closed end 6 thereof terminates a slight distance above the base ring 1.

The lower or closed end 6 of the casing C at substantially the axial center thereof is provided with an opening 7 through which extends a pin or cylindrical lug 8 carried by the bottom of the well W. 9 denotes an arm underlying the bottom or closed end 6 of the casing C and engaged therewith for 80 swinging movement. An end portion of the arm 9 is provided with a notch or recess 10 to receive the reduced portion 11 of the pin or lug 8 whereby the well W is effectively applied within the casing C.

The well W is of a diameter materially less than the diameter of the casing C, but is of a length in excess of the length of the casing so that the burner B engaged with the upper end portion of the well W is arranged above 95 the casing C. The lower portion of the side wall of the casing C is provided with air openings 12 for a well known purpose.

Coacting with and supported by the upper or open end portion of the casing C is the 100 transparent globe or shade G of any ordinary or preferred construction, and which is what is termed the "white light."

Positioned between the lower portions of adjacent members 3 and supported thereby 105 and by the base ring 1 and the casing C is a receptacle R which is adapted to contain torpedoes or the like whereby the use of my

improved lantern by railroad men is made more desirable. As is particularly illustrated in Fig. 1, the receptacle R is provided with a sliding door 14 so that suitable access 5 may be had within the receptacle R.

Soldered or otherwise secured to the upper portions of the side member 3 is an annular bracing or reinforcing member 15. The member 15 serves as a support for the diametrically opposed hollow or tubular portions of the handle member H. The lower end portion of the member H is soldered or otherwise secured to the base ring 1 and to the lower end portion of an adjacent member 3. The upper end portion of the handle H is provided with the cross member or hand grasp whereby the lantern may be readily manipulated.

The handle H is adapted to have stored therein fuses or the like. The outer face of each row or portion of the handle H is provided with an elongated opening 16 extending longitudinally thereof and throughout substantially its entire length, and which 20 affords means whereby fuses may be applied or removed from within the handle. Coacting with the opening 16 is a hinged closure member or door 17 which is preferably of a length in excess of the length of the opening 25 16 and coacting with the upper end portion of said door is a ring 18 slidably mounted upon the handle H and adapted to overlie the upper end portion of the door 17 for maintaining the same in closed position. 30 When it is desired to open the door 17 it is only necessary to move the ring 18 to a position free of the door 17. As illustrated in Fig. 6, the handle H' is provided at opposite sides of the longitudinally disposed 35 opening 16' with the guideways 19 with which coact the marginal portions 20 of a sliding closure member 21. The member 21 substantially midway its length is provided with a handle 22 so that the desired moving 40 45 of the member 21 in order to properly open or close the opening 16' may be effected with facility.

As illustrated in Fig. 7, the handle member H'' has coacting therewith a tubular section 23 telescopically engaged therewith, and which is held in applied position by a spring 50 latch 24 secured to the open end portion of the handle H'' and coacting with an outwardly directed pin 25 carried by the outer 55 end portion of the telescopic section 23.

The side wall of the casing C is provided with a slot 26 extending substantially the entire length thereof and disposed through said slot is an arm 27 extending outwardly 60 from the lower end portion of the screen holder M. Said arm 27 inwardly of its outer end is provided with the oppositely directed wings 28 which overlie the outer and inner faces of the side wall of the container C so that the arm 27 is conveniently

supported for sliding movement along the slot 26 and is maintained in substantially a horizontal position or in a position at right angles to the side wall of the casing C.

The holder M includes an annular member 29 occupying a plane parallel to the longitudinal plane of the arm 27 and the lower or inner marginal portion of said member 29 is defined by an inwardly directed flange 30 which serves as a seat for an end portion of the color screen S. The member 29 is spaced from the arm 27 and the inner portion of said arm 27 and the member 29 are connected by a substantially rigid strip or arm 31.

The screen, as herein disclosed, comprises 80 a cylindrical tubular body of transparent material of any desired color, preferably green, and the opposite end portions of said screen S are protected by the metallic annular members 32. The members 32 are 85 connected by the strips 33 arranged in imposed pairs and between which the transparent sheet 34 is arranged so that said sheet 34 is held in applied position.

When the arm 27 is at the limit of its 90 movement in the direction away from the burner B the screen S is in a position below or inwardly of the burner B so that the rays emitted from the lantern are "white". When it is desired that such rays of light be 95 colored for purposes necessary to the duties of a trainman or the like, the arm 27 is forced upwardly, and which results in positioning the screen S to inclose the burner B or more particularly the flame thereof. 100 Depending from the upper or top marginal portion of the side wall of the casing C and overlying the outer face thereof is a spring arm 35 arranged in close proximity to the slot 6. When the arm 27 is forced 105 upwardly one of the outer wings 28 passes beneath the spring arm 35 so that the arm 27 or more particularly the holder M is held against downward movement. The inner or free end portion of the arm 35 is provided with an inturned lip 36 which engages beneath the coacting wing 28 so that a positive means is provided to hold the arm 27 against downward movement.

The member 29 is provided at equidistantly spaced points with a plurality of bayonet slots 37 opening inwardly and each of which is adapted to receive an outstanding pin or lug 38 carried by the lower member 32. By this means the screen S may be readily detached or applied so that screens of different colors may be employed as required or a screen unfit for use may be readily replaced.

From the foregoing description, it is 125 thought to be obvious that a lantern constructed in accordance with my invention is particularly well adapted for use by reason of the convenience and facility with which it may be assembled and operated, 130

and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

10 I claim:

1. A lantern of the class described comprising a casing having one end open, a side wall of the casing being provided with a slot, a burner supported by the casing and positioned outwardly of the open end thereof, an arm disposed through the slot of the casing, oppositely directed pairs of wings carried by the arm and engaging the opposite faces of the side wall of the casing, and a color screen carried by said arm.
2. A lantern of the class described comprising a casing having one end open, a side wall of the casing being provided with a vertically directed slot, a burner supported by the casing and positioned outwardly of the open end thereof, an arm disposed through the slot of the casing, oppositely directed wings carried by the arm and engaging the opposite faces of the side wall of the casing, a color screen carried by said arm, and a downwardly directed spring arm carried by the casing adjacent an end portion of the slot, said spring arm coacting with a wing of the first named arm for holding said first named arm at substantially its limit of movement in one direction, the free extremity of said spring arm being provided with an inwardly directed lip coacting with the inner marginal portion of the wing, whereby said spring arm positively holds the first named arm at its limit of movement in one direction.

In testimony whereof I hereunto affix my signature in the presence of two witnesses. 60

JOSEPH NORMAN KLEMA.
